Inventor.

Jacob Straus, by
Geo. S. Prindle, his Atty.

UNITED STATES PATENT OFFICE.

JACOB STRAUS, OF ST. LOUIS, MISSOURI.

COMBINED TRACE-BUCKLE AND COCKEYE.

SPECIFICATION forming part of Letters Patent No. 243,322, dated June 21, 1881.

Application filed May 6, 1881. (Model.)

To all whom it may concern:

Be it known that I, JACOB STRAUS, of St. Louis, in the county of St. Louis, and in the State of Missouri, have invented certain new and useful Improvements in Combined Trace-Buckle and Cockeye; and I do hereby declare that the following is a full, clear, and exact description thereof, reference being had to the accompanying drawings, making a part of this specification, in which—

Figure 1 is a perspective view of my device separate from a trace and single-tree. Fig. 2 is a like view of the same as combined with said parts, and Fig. 3 is a central longitudinal section upon a horizontal line.

Letters of like name and kind refer to like parts in each of the figures.

The design of my invention is to furnish a more convenient means for connecting a trace with a single-tree than has heretofore been obtainable; and to this end it consists, broadly, in a trace-buckle and cockeye combined in one part, substantially as and for the purpose hereinafter specified.

It consists, further, in the construction and combination of the frame of the buckle and the tongue, substantially as and for the purpose hereinafter shown.

It consists, finally, in the device as a whole, its several parts being constructed and combined to operate in the manner and for the purpose substantially as hereinafter set forth.

In the annexed drawings is shown the frame of my buckle, composed of two side bars, A, and end bars, B and C, which are arranged in a rectangular form in side elevation, while in plan view said frame has a semicircular form, caused by the curving of said side bars, A.

Journalized transversely within the outer edges of the side bars, A, nearest the cross-bar B, is a roller, D, from the center of which projects radially a tongue, d, that is curved toward said bar B, and at its end upon the side opposite to said bar has a hook or barb, d', as shown in Fig. 1. From the base of said tongue a short broad lug, d², extends rearward at nearly a right angle to the same, and completes the buckle portion of my device, which is connected with a trace in the following manner, viz: The tongue d is turned rearward to the position shown by dotted lines of Fig. 3, and

the end of the trace E passed beneath the bar B over said tongue, and then beneath the bar C, after which said tongue is turned outward and forward until its end enters a hole, e, 55 provided for its reception in said trace, and the latter is then moved longitudinally forward. The tongue d under a heavy strain has its end supported by or upon the bar B, which prevents further movement in such direction, but under ordinary strains is held at a short distance from said bar by the action of the lug d², which bears against the rear side of said trace, and causes the latter to be bent sharply outward whenever said tongue passes 60 forward of the position shown in Figs. 2 and 3. The operation of the lug d² is to prevent the jamming of the trace E within the buckle, the spring of said trace, operating through said lug, being sufficient to cause the tongue 65 d to be moved rearward from contact with the bar B as soon as strain is removed from said parts.

Upon the rear end of the frame is formed a cockeye, F, which enables the device to be 75 attached to or upon a single-tree, G. Said cockeye has preferably the form shown; but any other form may be employed to suit the taste or that may be necessary to adapt the device to any particular form of single-tree. 80

If desired, the entire metal portion of the cockeye may be omitted, and in its place substituted a leather cockeye or loop, the front end of which will pass around and be secured to the rear bar, C.

By the use of this device, as no part is permanently connected to the trace, a material saving is effected in the cost of making the latter, as it can be entirely stitched upon a machine, instead of requiring to be partly 85 stitched by hand, as has heretofore been necessary.

Having thus fully set forth the nature and merits of my invention, what I claim as new is—

1. Broadly, a trace-buckle and cockeye combined in one part, substantially as and for the purpose specified.

2. The combination of the roller D, provided with the tongue d and lug d², with the rectangular curved frame described, substantially 90 as and for the purpose shown.

3. The hereinbefore-described device, consisting of the frame A, B, and C, roller D, provided with the tongue d' and lug d^2 , and the cockeye F, said parts being combined with each other and adapted for connection with a trace, E, and single-tree G, in the manner and for the purpose set forth.

In testimony that I claim the foregoing I have hereunto set my hand this 4th day of May, 1881.

JACOB STRAUS.
